Patented Nov. 2, 1965

202,694

POLISHING MACHINE

Jerome D. Rosenberg, 3 Shadow Lawn Drive,
Livingston, N.J.

Filed Oct. 1, 1964, Ser. No. 81,977

Term of patent 14 years

(Cl. D9—2)

FIG.—1—

FIG.—4—

FIG.-2-

FIG.-3-

FIGURE 1 is a top plan view of a polishing machine embodying my new design;

FIGURE 2 is an elevational view showing the right side of the machine;

FIGURE 3 is an elevational view showing the front of the machine; and

FIGURE 4 is an enlarged cross-sectional view taken along the line 4-4 of FIGURE 3.

The dominant features of my design reside in the portions shown in full lines.

I claim:

The ornamental design for a polishing machine, as shown and described.
